UNITED STATES PATENT OFFICE.

GLENN ANDREW JOHNSON, OF McPHERSON, KANSAS.

BOOK SUPPORT.

Application filed November 16, 1923. Serial No. 675,172.

To all whom it may concern:

Be it known that I, GLENN A. JOHNSON, a citizen of the United States, residing at McPherson, in the county of McPherson and 5 State of Kansas, have invented certain new and useful Improvements in Book Supports, of which the following is a specification.

This invention relates to a support for holding a book, magazine, newspaper, picture or mirror at various angles between 10 two extremes, the device being thus adjustable to suit the position of the user.

An important object is the provision of a support provided with means for holding 15 a book or magazine open at the proper angle so that each page will be approximately in a plane perpendicular to the visual axes of the eyes of the reader so that strain will be avoided.

20 Another object is the provision of a device of this character provided with leaf engaging means for positively maintaining the leaves against casual turning, this element or member being deformable so as to release 25 the pages or leaves by an extremely simple operation.

Still another object is the provision of a holder of this character which is so constructed that when not in use it may be 30 folded into a compact bundle, the leaf holding member operating, in this instance, to maintain the various parts in their collapsed position.

An additional object is the provision of a 35 device of this character which will be simple and inexpensive in manufacture, efficient and durable in service, and a general improvement in the art.

With the above and other objects and advantages in view, the invention consists in the combination and arrangement of the several parts to be hereinafter more fully described and claimed and illustrated in the 40 accompanying drawings, in which:

45 Figure 1 is a perspective view of the device set up for use.

Figure 2 is a detail perspective view showing the upper ends of the various supporting members disconnected.

50 Figure 3 is a fragmentary rear elevation of the horizontal support.

Figure 4 is a detail cross section on the line 4-4 of Figure 3.

Figure 5 is an edge elevation of the device showing it folded or collapsed. 55

Figure 6 is a front elevation thereof or a view at right angles to Figure 5.

Figure 7 is a detail view on the line 7-7 of Figure 5.

Referring more particularly to the drawings, the numerals 10 and 11 designate the two main or front uprights which are formed as elongated strips of suitable material, preferably metal, which may be nickel plated or otherwise finished to have a pleasing appearance and to avoid rusting. These two members are designed to be pivotally connected at their upper ends and for this reason the former is formed with an elongated slot 12 which is adapted to register 60 with a circular hole 13 in the latter. The upper end of the member 11 is angularly deflected, as indicated at 14, and it is this deflected end which is not only formed with the hole 13 but also with a pair of spaced 65 slits or cuts 15 which define a tongue 16 which may be bent out, if necessary, to form a prolongation of the hole 13.

Associated with the main members 10 and 11 is a leg or brace 17 which is likewise 80 formed as an elongated strip having its upper end cut to define a central tongue 18 terminating in a T-shaped head 19. The formation of this central tongue also defines a pair of side tongues 20 which are curved in 85 a direction which is opposite to the direction of curvature of the tongue 18. The head 19 is intended to be inserted and in fact is inserted through the slot 12 and hole 13, it being probably necessary to bend out the 90 tongue 16 to facilitate or permit this operation, after which the tongue 16 is bent back into its normal or initial position. The tongue 18 thus constitutes connecting means for the upper ends of the front members 10 95 and 11 and the head 19 operates to prevent accidental disconnection, it being obvious that to effect separation it will be necessary to turn the brace 17 to bring the head 19 into registration with the slot 12 and to press out the tongue 16 so that the head may subsequently be brought into registration with

100

the resultant slot. The ends of the tongues 20 engage against the rear side of the angularly deflected upper end of the member 11 so that the proper bracing action will be had. The lower ends of the members 10, 11 and 17 are shod with rubber tips or feet 21 to prevent marring or scratching the top of a table or other surface upon which the device may be used.

10 Connecting the members 10 and 11 near the lower ends thereof, is a horizontal supporting bar 22 which is pivotally connected at 23 and 24 with the members 10 and 11, respectively. Near the pivot 23 the bar 22 is offset, as indicated at 25, while near the pivot 24 it is doubly offset, as indicated at 26 and 27. The offsetting is particularly for the purpose of permitting folding of all the strips into compact position, as shown in Figure 5 and also to define supporting means for the cover or back of a book, magazine or the like.

15 The leaf retaining means is of a deformable nature and is formed from a single length of wire indicated broadly by the numeral 28, the central portion of the wire being bent upon itself, as shown at 29, to define what may be called arms 30 which lie in a plane rearwardly of the plane of the bar 22 and which are formed at their meeting ends with a downwardly and forwardly and then upwardly arranged hook 31 which is adapted to be engaged for pulling the arms 30 out of engagement or contact with the leaves of the book or magazine to permit turning thereof. The end portions 32 of this wire member 28 lie against the offset ends of the bar 22 and extend through holes 33 in the bar, from which point the ends of 20 the wire are brought back in contact with the rear side of the ends of the bar and held beneath tongues 34 which are stamped out from the bar 22 and which are coiled or clenched about the terminals of the wire.

25 In the use of the device for holding a newspaper or the like, it is employed in substantially the same manner as an easel and it can be used in this same manner for supporting a picture, mirror or the like. In 30 order to effect holding of a book or magazine, the back is engaged against the front members 10 and 11 with the lower edge of the back or cover engaged upon the forwardly offset ends of the bar 22. The arms 30 which constitute the leaf holding means engage resiliently against the leaves and prevent them from accidental turning so that the user may read in comfort and without holding the reading matter manually. 35 Whenever it is desired to turn the leaves, it is merely necessary that the operator engage a finger within the hook 31 and pull downwardly thereon to bring the arms 30 forwardly and away from the leaves and out of 40 obstructing relation thereto so that the

leaves may be turned freely to the desired point, after which release of the hook will permit the arms 30 to return to their leaf engaging position.

When use of the device is not desired, the 70 brace 17 is turned so that the head 19 will register with the slot 12, whereupon the member 10 is disengaged from the head 19 and swung to lie flat against the rear side of and in registration with the bar 22, the 75 slotted end terminating at the offset 26. The member 11 lies flat against the rear side of the member 10, while the brace 17 is turned, without disconnection from the member 11 and is swung thereagainst, the parts being 80 then arranged as shown in Figures 5, 6 and 7. When this is done the hook 31 is engaged under the assembled strips while the arms 30 engage over them or at the opposite edge so that the various strips will be positively held in a neat and compact bundle which may be easily carried within the 85 pocket or within a traveling bag or the like.

From the foregoing description and a study of the drawings it will be apparent 90 that I have thus provided a simply constructed, inexpensive, neat and attractive, and highly efficient support for the purpose specified which will perform all the functions for which it is intended and which, on account of its simplicity, is practically incapable of getting out of order.

While I have shown and described the preferred embodiment of my invention, it is of course to be understood that I reserve the 100 right to make such changes in the form, construction and arrangement of parts as will not depart from the spirit of the invention or the scope of the subjoined claims.

105 I claim:—

1. A device of the character described comprising supporting legs pivotally connected in upwardly converging relation, a brace pivotally connected with said legs, means for limiting swinging movement of the brace with respect to the legs, a bar pivotally connected with the legs, and leaf holding means on the bar, the legs and bar being foldable to lie in registration, and said leaf holding means operating to hold the legs 110 and bar in folded position.

2. A device of the character described comprising supporting legs pivotally connected in upwardly converging relation, a brace pivotally connected with said legs, 120 means for limiting swinging movement of the brace with respect to the legs, a bar pivotally connected with the legs, and leaf holding means on the bar, one of said legs being detachable from the other and from said brace whereby to be swingable to lie against the bar, and the other leg and brace being swingable to lie together in registration with the bar and first named leg, said leaf holding means being engageable with 125

the folded bar, legs and brace for holding the same in registering position.

3. In a device of the character described, a pair of leg members connected by a cross bar pivotally connected therewith and arranged in upwardly converging relation, the upper end of one leg being formed with an elongated slot and the other being formed with a hole and slits arranged in spaced relation and leading thereto to define a bendable tongue, and a brace having its upper end formed with a constricted neck and a head insertible through said hole and slot and held by said tongue.
- 10 4. In a device of the character described, a pair of leg members connected by a cross bar pivotally connected therewith and arranged in upwardly converging relation, the upper end of one leg being formed with an elongated slot and the other being formed with a hole and slits arranged in spaced relation and leading thereto to define a bendable tongue, and a brace having its upper end formed with a constricted neck and a head insertible through said hole and slot and held by said tongue, the brace being further formed with curved tongues arranged laterally of said neck and engageable with the
- 20
- 25

rear side of the second named leg whereby to limit movement of the brace with respect thereto.

5. In a device of the character described, a pair of leg members connected by a cross bar pivotally connected therewith and arranged in upwardly converging relation, the upper end of one leg being formed with an elongated slot and the other being formed with a hole and slits arranged in spaced relation and leading thereto to define a bendable tongue, and a brace having its upper end formed with a constricted neck and a head insertible through said hole and slot and held by said tongue, the brace being further formed with curved tongues arranged laterally of said neck and engageable with the rear side of the second named leg whereby to limit movement of the brace with respect thereto, and said brace being rotatable to bring the head thereof into registration with said slot to permit disconnection of the first mentioned leg therefrom whereby the legs and brace may be folded to lie in superposed relation aganist the bar.

In testimony whereof I hereby affix my signature.

GLENN ANDREW JOHNSON.
